MANUFACTURE OF CARTRIDGE LINKS

Alwyn E. Borton, South Orange, N. J., assignor to
 Associated Patentees, Inc., Ampere, N. J., a corporation of New Jersey

Application November 14, 1941, Serial No. 419,062

12 Claims. (Cl. 59—3)

The invention here disclosed relates to the manufacture of the links by which machine gun cartridges are connected together in belt formation.

These links are cut and formed from strip stock and a special object of the invention is to avoid, so far as possible, waste of the stock.

In accomplishment of this object, a special feature of the invention is the utilization of the full width of the strip stock in manufacture of the links.

Other special objects are to attain high speed, low cost, continuous production and to fully protect the machinery required for such manufacture of the links.

Additional objects will appear as the specification proceeds.

The novel features of invention are herein-after set forth and broadly claimed.

The drawings accompanying and forming part of the following specification illustrate a practical and preferred embodiment of the invention, but it is realized that modifications and changes may be made all within the true intent and broad scope of the invention and such illustration is therefore to be taken primarily by way of disclosure.

Referring to such drawings,

Fig. 1 is a side elevation of one of the links.

Fig. 2 is a top plan or end view of the same.

Fig. 3 is a broken side view of the strip stock illustrating successive stages in the piercing, shearing and forming operations. Fig. 3a is a top plan or edge view of the same.

Fig. 4 is a compound view illustrating successive bending operations performed on the severed blank at the upper level of the final station, parts appearing in section as on substantially the plane of line 4—4 of Fig. 10.

Fig. 5 is a similar horizontal sectional view on substantially the plane of line 5—5 of Fig. 10, illustrating the final forming operation performed at the lower level.

Fig. 6 is a broken side view showing successive steps in the operation of sizing and "flaring" the lower ring or ferrule of the link.

Fig. 7 is a broken part plan and sectional view of the machine for performing all the various operations required. Figs. 7a and 7b are face views of companion die elements at the first front slide.

Fig. 8 is an enlarged vertical section view as on substantially the line 8—8 of Fig. 7, showing in particular the mechanism for ejecting the small intervening pieces between adjoining

blanks on the strip, at the stage designated as C in Figs. 3 and 7.

Fig. 9 is a further enlarged broken and part sectional view of the head and plunger mechanism at the final station as on substantially the plane of line 9—9 of Fig. 7.

Fig. 10 is a broken vertical sectional view as on substantially the plane of line 10—10 of Fig. 9.

Fig. 11 is a horizontal sectional detail as on substantially the line 11—11 of Fig. 9, illustrating the engagement of the forward blank with the stock detector and showing the position of the stripper above the stock.

Fig. 12 is a diagrammatic view of the parts for checking the feed of the stock and controlling operation of the machine accordingly.

As shown particularly in Figs. 1 and 2, the links consist each of a single piece of sheet metal formed at one end with axially spaced concentric rings or loops 15, 16, of a size to receive a machine gun cartridge and at the opposite end with a single ring or loop 17, to enter between the spaced loops of an adjoining link, thus to utilize the cartridges as hinge pins for connecting the links in a continuous web or chain.

The ring 16, which receives the tapered bullet-end of the cartridge is shown as narrower than the companion ring 15, which receives the firing end of the cartridge and is shown as contracted at 18, to lesser diameter to fit the bullet and as flared at 19, to receive the contracted end portion of the cartridge shell.

The intermediate body portion 20, of the link is shown as embossed at 21, at the center on a curvature corresponding to and forming part of the internal outline of the intermediate hinge loop 17, this embossment offsetting this loop slightly from the concentrically curved outline of the intermediate connecting wall 20, as indicated in Fig. 2.

Fig. 3 illustrates a strip 22, of the stock material from which the links are formed and shows at A, B, C, D, E and F, the successive steps of piercing, shearing, trimming away the ends of adjoining blanks, preforming the intermediate body portions, severing and finally bending the rings, and the stations at which these operations are performed are indicated by the corresponding letters in Fig. 7.

In the present disclosure, all these operations are performed substantially simultaneously, or as parts of a single cycle on a so-called "Multi-slide" machine (Borton Patent 1,883,513, October 18, 1932).

Figs. 7, 8, 9, 10, 11, show essential details of

the machine as constituted to carry out manufacture of the links, particularly the base or bed 23, on which the tool carrying slides are mounted and the front, back and right-hand end shafts 24, 25, 26, carrying the cams for actuating the slides and other parts.

In this machine, the strip stock enters on-edge at the left in Fig. 7, and is advanced intermittently, with a dwell sufficient for the tool operation at each station.

The piercing tools 27, for punching the initial openings 28, the tools 29 for shearing at 30, from these openings along the sides of the hinge loop 17, about the rounded shoulders of the body portion 20, and the tools 31, for trimming the ends of the ring portions 15 and 16, to the desired length and taper at 33, 34, are all mounted on the same slide 35, actuated by cam (not shown) and rocker movement from the front cam shaft 24, as in the "Multi-slide" patent.

Similarly, the tool 36, for embossing the curved offset 21, and the shear block 37, for the cutoff tool are both carried by slide 38, actuated by cam and rocker from the front cam shaft.

The stationary back plates 39 and 40, carry the elements cooperative with the front tools. Thus the plate 39 has die openings 41, for the piercing tools 27; a yielding shear block 42, cooperative with the shearing tool 29, and shearing edges at 43, cooperative with the shearing tool 31; and the plate 40, carries the convex die element 44, cooperative with the preforming tool 36, and the knife 45, cooperative with the block 37, for cutting both ends of the short neck piece 46, left at that point connecting the end of the hinge loop 17, of one blank with the intermediate body portion 20, of the succeeding blank.

To clear out the small pieces of scrap at 47, 48, Fig. 3, between the end of one blank and the back or body portion of the preceding blank, a special ejector is provided in the form of two plungers 49, 50, Fig. 8, having smaller end faces than said scrap pieces; said plungers being carried by a back slide 51, and projecting forwardly at the end of back plate 39, closely adjacent the shearing tools 31, 32-43. The slide 51 is pivotally connected at 52, with a rock lever 53, pivoted on the back of the base at 54, and carrying a roll 55, riding the cam 56, on the back shaft 25. The upper end of the lever is rocked forwardly by a spring 57, acting on a link 58, shackled to the lever at 59, thus to yieldingly project the plungers and hold the roll engaged with the cam, the extent of projection being controlled by an adjustable stop screw 60, in the upper end of the lever 51, engageable with the back of the bed.

The cam 56 is shown as circular except for a short dip 61, at one point, to hold the plungers 49, 50, retracted, up to the instant of scrap ejection. These plungers however, can yield to the pressure of the pieces of scrap 47, 48, as they are cut free by the shearing tools, but react as the front shearing tools retreat, to press the cut pieces back into the cavities; said plungers then being projected after the shearing tools are in the clear, by the lever roll 55, dropping in the cam depression to push the scrap pieces forwardly to a point where they will drop away from the stock.

Suitable guides may be provided for accurately positioning and directing the strip and, since the full width of the strip is utilized, the strip may be guided all the way through the machine by direct engagement with the upper and lower edges of the same. Also for control purposes,

the strip may be gripped at one or more points as by a spring pressed plunger or plungers, such as indicated at 62, 62, in the tool slide 35 and back plate 39. The pad 63, at the sides of the preforming tool 36, on the second tool slide 38, may also apply a holding pressure to the stock.

The double edged cut-off knife or punch 45, may be operated by a special cam (not shown) from the back cam shaft 25, to effect severance 10 of the first blank at station E, just after the pre-forming of the intermediate body portion of the adjoining blank, to which it is then still attached at station D. To provide clearance for the offset formed in the stock by the preforming operation, the shearing block 37, Figs. 4 and 7, is shown cut back at 64, to receive that part of the blank just to the rear of the shearing tool 45, Fig. 3.

At the final forming station F, the first blank 20 while still attached to the strip, passes in front of the two bending posts 65, 66, Figs. 4 and 9. As the cutter effects severance of this blank, the front bending slide 61, advances and the intermediate round pointed tool 68, striking the upper and lower ring portions 15, 16, at the end of the 15 curvilinear preforming indicated at D, in Fig. 3, bends such arms around mandrel 66, and carries the preformed body portion around mandrel 65, and while this indentation is being effected, the left portion 69 of this tool bends the hinge loop 17, about the outside of mandrel 65, while the right portion 70, carries the ring forming straps 15, 16, about the outer side of mandrel 66.

On the completion of this first stage as shown at the top in Fig. 4, with the front tool slide fully in, the back tool 71, comes in as shown in the lower view of Fig. 4, to bend the straps or arms 15, 16, 17, inwardly into partially completed ring formation over the forming piece 72, Fig. 10, at the back of post 65 and 66.

At the time when the first blank is cut free and the front tools start indenting and closing the ring portions about the forming posts, the upper and lower ring portions 15, 16, of the next blank, Figs. 4 and 9, stand in front of spaced fingers 73, 74, projecting from the end of back plate 40, and so are supported and held so that they can not follow the hinge loop portion 17, as that portion is picked up and bent backwardly from between the upper and lower ring portions 15, 16, by the left bending portion of the front tool assembly.

Upon retraction of the back tool 71, Fig. 10, a stripper 75, Figs. 9 and 11, carried by plunger 76, is actuated by lever 77, to slip the partially formed link down over the posts 65, 66, to the lower level position indicated in Figs. 5 and 6.

The back tool 71, has a lower, ring-closing tool face 78, Fig. 10, which on the next inward stroke of the tool completes the closing of the three ring-forming portions 15, 16, 17, about the posts 68 and 65, Fig. 5.

The top view in Fig. 6 shows this condition of the piece and in particular that the lower narrower ring element 16, at the time is closed about the cylindrical portion 79, of the lower end of the plunger 80, operating within the post 68, and which latter is tubular to form a guide and support for said plunger. Tool extensions 81, 82, Fig. 10, at the bottom of the front and rear tool slides 61, 61, cooperate to close the lower ring portion to reduced diameter about the cylindrical plunger portion 79.

To hold the piece down in position for this ring reducing operation, a spring catch is shown in the form of a slide 83, Fig. 10, set in the back tool 75 and pressed forwardly by spring 84, said holding

slide having a bevelled front face 85, which will enable the lower partly formed ring to force said slide back, so that it can snap out over the upper edge of the ring when the stripper has forced the piece downward fully into position between the tools.

The lower view in Fig. 6, with Fig. 10, shows how after the rings are fully closed, the plunger 80, comes down to cause the flaring tool 86, forming part of the same to expand the upper edge portion of ring 16, over the correspondingly inclined upper edge portions 87, 88, of the ring closing tools 81, 82.

To brace and center the flaring tool at the bottom, the lower cylindrical end portion of the tool may enter a forked socket 89, provided for the purpose, on a slide 89a, as indicated in Figs. 9 and 10.

The stem or plunger portion 80, of the flaring tool is indicated in Fig. 9, as pivotally connected at the upper end at 90, with a lever 91, pivoted to rock on a center 92. This lever and the lever 77, for actuating the stripper are shown in Fig. 7, as pivotally mounted on the opposite sides of the head structure 93, and operated from cams 94, 95, on the right end cam shaft 26.

The small pieces of scrap which are struck out of the strip are disposed of to prevent any possible jamming or injury to the machine. This first little wedge-shaped pieces struck out at 28, the small pieces at 47, 48, between adjoining blanks, pushed out by the ejector fingers 49, 50, and the narrow connecting link cut out at 45, may all drop through suitable discharge openings provided in the bed.

To protect the machine against possible injury should anything happen to prevent the stock reaching the final operating station, special means are provided in the form of a detector finger 96, Fig. 12, engageable by the front blank, before severance from the strip, to close a control circuit which maintains the machine in running condition. This detector finger is shown pivotally mounted at 97, and as operating a plunger 98, to close a switch indicated diagrammatically at 99, as forming part of a circuit 100, for the electric brake mechanism at 101, which is operable to throw out the clutch and apply a brake to the flywheel 102, if this circuit is open at a time when the front end of the stock should have reached the final station.

To carry the load of this control circuit during the balance of the cycle, there is provided in the illustration, a branch circuit 103, in parallel with the detector circuit 99, 100, and containing a normally closed switch 104, adapted to be opened by a lever 105, under operation of a cam 106, on the front cam shaft 24, at the time when the stock should have reached and be closing the circuit at the detector station.

In this way, the machine is maintained in operation so long as stock is being properly acted upon and reaching the final operation station and the action is checked for each cycle by interrupting the normal running circuit and substituting the detector circuit at the time when the stock should be present at the final station.

With these precautions, the machine may be operated continuously at high speed. The full width of the strip is used so there is no need to trim away one edge or the other and both edges of the stock can be utilized for guiding purposes. By using the full width of the strip, the percentage of scrap is kept very low.

The preforming at 21, stiffens the body portion

of the blank and initiates the points of reverse bending at 107, Fig. 3, for the ring forming elements 15, 16.

The flaring tool 86, operates in addition as a means for accurately centering the contracted ring 16, coaxially with the companion ring 15. Further, in the illustration, this flaring tool effects a "sizing" of the link, definitely establishing a desired spacing between the upper and lower rings 15, 16, and actually, if desired, stretching the piece transversely to increase the overall width above and beyond that of the original strip. By means of this "sizing," links of a desired width can be produced from strip stock of less than that particular width, providing consequent saving in material.

In this "sizing" operation and particularly if there is any stretching or increasing of the transverse dimension of the link, the right hand slide 89a, serves as an anvil, as indicated in Fig. 10, to support the lower edge of the bottom loop 16, and determine final position of the same after it has been carried downward in the flaring operation away from the upper loop 15, clamped at the time between the closed front and rear tools.

What is claimed is:

1. The method of manufacturing cartridge links from the full width of strip stock, which comprises piercing the intermediate portion of a strip to form therein two transversely spaced pierced portions, shearing the stock inwardly from the extreme outer edges and longitudinally to said pierced portions to define adjoining blanks with an intermediate longitudinally extending tongue of one blank between longitudinally extending side tongues of the adjoining blank and constituting edge portions of the strip, severing the end blank from the series of blanks in formation and bending the intermediate and side tongues of the severed blank into ring formation.

2. The method of manufacturing cartridge links from the full width of strip stock, which comprises piercing the intermediate portion of a strip to form therein two transversely spaced pierced portions, shearing the stock inwardly from the extreme outer edges and longitudinally to said pierced portions to define adjoining blanks with an intermediate longitudinally extending tongue of one blank between longitudinally extending side tongues of the adjoining blank and constituting edge portions of the strip, severing the end blank from the series of blanks in formation and bending the intermediate and side tongues of the severed blank into ring formation and concentrically contracting and coaxially flaring one side tongue of said blank in respect to the other side tongue of the same.

3. The method of manufacturing cartridge links from the full width of strip stock, which comprises piercing the intermediate portion of a strip to form therein two transversely spaced pierced portions, shearing the stock inwardly from the extreme outer edges and longitudinally to said pierced portions to define adjoining blanks with an intermediate longitudinally extending tongue of one blank between longitudinally extending side tongues of the adjoining blank and constituting edge portions of the strip, severing the end blank from the series of blanks in formation and bending the intermediate and side tongues of the severed blank into ring formation and prior to such severance of the end blank longitudinally embossing the same in arcuate formation in the intermediate portion of the

blank connecting said intermediate and side tongues.

4. The method of manufacturing cartridge links from the full width of strip stock, which comprises piercing the intermediate portion of a strip to form therein two transversely spaced pierced portions, shearing the stock inwardly from the extreme outer edges and longitudinally to said pierced portions to define adjoining blanks with an intermediate longitudinally extending tongue of one blank between longitudinally extending side tongues of the adjoining blank and constituting edge portions of the strip, severing the end blank from the series of blanks in formation and bending the intermediate and side tongues of the severed blank into ring formation and in said piercing and shearing operations leaving the end of the intermediate tongue of one blank connected with the intermediate portion, between the side tongues of the adjoining blank.

5. The method of manufacturing cartridge links from the full width of strip stock, which comprises piercing the intermediate portion of a strip to form therein two transversely spaced pierced portions, shearing the stock inwardly from the extreme outer edges and longitudinally to said pierced portions to define adjoining blanks with an intermediate longitudinally extending tongue of one blank between longitudinally extending side tongues of the adjoining blank and constituting edge portions of the strip, severing the end blank from the series of blanks in formation and bending the intermediate and side tongues of the severed blank into ring formation and in said piercing and shearing operations leaving the end of the intermediate tongue of one blank connected with the intermediate portion, between the side tongues of the adjoining blank in the form of a narrow tongue and in the severing of the end blank, cutting both ends of said narrow connecting tongue.

6. The method of manufacturing cartridge links from the full width of strip stock, which comprises piercing the intermediate portion of a strip to form therein two transversely spaced pierced portions, shearing the stock inwardly from the extreme outer edges and longitudinally to said pierced portions to define adjoining blanks with an intermediate longitudinally extending tongue of one blank between longitudinally extending side tongues of the adjoining blank and constituting edge portions of the strip, severing the end blank from the series of blanks in formation and bending the intermediate and side tongues of the severed blank into ring formation, in two stages partially at one position and then shifting the blank and completing the ring form bending at another position.

7. The method of manufacturing cartridge links from the full width of strip stock, which comprises piercing the intermediate portion of a strip to form therein two transversely spaced pierced portions, shearing the stock inwardly from the extreme outer edges and longitudinally to said pierced portions to define adjoining blanks with an intermediate longitudinally extending tongue of one blank between longitudinally extending side tongues of the adjoining blank and constituting edge portions of the strip, severing the end blank from the series of blanks in formation and bending the intermediate and side tongues of the severed blank into ring formation and in said shearing operations, cutting material free between adjoining blanks and

forcing that material back through the cuts and clear of the stock in process.

8. The method of manufacturing cartridge links from the full width of strip stock, which comprises piercing the intermediate portion of a strip to form therein two transversely spaced pierced portions, shearing the stock inwardly from the extreme outer edges and longitudinally to said pierced portions to define adjoining blanks with an intermediate longitudinally extending tongue of one blank between longitudinally extending side tongues of the adjoining blank and constituting edge portions of the strip, severing the end blank from the series of blanks in formation and bending the intermediate and side tongues of the severed blank into ring formation and performing said piercing, shearing, severing and bending operations by horizontal movements and with the strip stock in vertically disposed on-edge relation.

9. The method of manufacturing cartridge links from the full width of strip stock, which comprises piercing the intermediate portion of a strip to form therein two transversely spaced pierced portions, shearing the stock inwardly from the outer edges at points longitudinally removed from said piercing and longitudinally to said pierced portions to define portions of adjoining blanks with an intermediate longitudinally extending tongue of one blank between and free from longitudinally extending side tongues of an adjoining blank constituting edge portions of the strip and connected by a back portion across the full width of the strip, removing material between the back portion and intermediate tongue of one blank and the ends of the side tongues of an adjoining blank to trim said side tongues to predetermined shape and relative spacing across the strip, embossing the back portion connecting the side tongues, severing the trimmed and embossed blank from the end of the strip and bending the intermediate and side tongues of the severed blank into ring formation.

10. The method of manufacturing cartridge links from the full width of strip stock, which comprises piercing the intermediate portion of a strip to form therein two transversely spaced pierced portions, shearing the stock inwardly from the outer edges at points longitudinally removed from said piercing and longitudinally to said pierced portions to define portions of adjoining blanks with an intermediate longitudinally extending tongue of one blank between longitudinally extending side tongues of an adjoining blank constituting edge portions of the strip and connected by a back portion across the full width of the strip, removing material between the back portion and intermediate tongue of one blank and the ends of the side tongues of an adjoining blank to trim said side tongues to predetermined shape and relative spacing across the strip, severing the trimmed blank from the end of the strip and bending the intermediate and side tongues of the severed blank into ring formation.

11. The method of manufacturing cartridge links from the full width of strip stock, which comprises piercing the intermediate portion of a strip with a pair of openings spaced transversely across the width of the strip, shearing the stock inwardly from the outer edges at points longitudinally removed from said piercing and longitudinally to said openings to define portions of adjoining blanks with an intermediate longitudinally extending tongue of one blank between longitudinally extending side tongues of an ad-

joining blank constituting edge portions of the strip and connected by a back portion across the full width of the strip, removing material between the back portion and intermediate tongue of one blank and the ends of the side tongues of an adjoining blank to trim said side tongues to predetermined shape and relative spacing across the strip; severing the trimmed blank from the end of the strip by removing the material between said spaced openings and bending the intermediate and side tongues of the trimmed and severed blank into ring formation.

12. The method of manufacturing cartridge links or the like, which comprises cutting a strip of stock transversely and longitudinally into por-

tions of adjoining blanks having an intermediate longitudinally extending tongue of one blank between longitudinally extending side tongues of an adjoining blank, constituting edge portions of the strip and connected by a back portion across the full width of the strip, severing the end blank from a series of blanks in formation, coiling the intermediate and side tongues of the severed blank into ring formation and then concentrically flaring the ring shaped formation of one of said side tongues of said blank in axial alignment with the ring formed by the other side tongue of said blank.

ALWYN E. BORTON.
